[57] CLAIM

The ornamental design for an upper portion of a vacuum cleaner, as shown and described.

DESCRIPTION

FIG. 1 is a front elevational view of an upper portion of a vacuum cleaner showing my new design;

FIG. 2 is a right side elevational view thereof;

FIG. 3 is a left side elevational view thereof;

FIG. 4 is a rear elevational view thereof with a portion of the coiled cord broken away;

FIG. 5 is a rear elevational view thereof with the cord and cleaner hose removed;

FIG. 6 is a top plan view thereof; and

FIG. 7 is a bottom plan view thereof.

The cord is partially removed in FIG. 4 and completely removed along with the vacuum cleaner hose in FIG. 5 for clarity of illustration only. The cross hatch pattern shown in FIGS. 1-5 is understood to repeat throughout the indicated area.
